UNITED STATES PATENT OFFICE

ALBERT KOTLAN, OF CICERO, ILLINOIS

DESIGN FOR A STOP LIGHT FOR AUTOMOBILES

Application filed August 4, 1931. Serial No. 40,782. Term of patent 3½ years.

To all whom it may concern:

Be it known that I, ALBERT KOTLAN, a citizen of the United States, residing at Cicero, in the county of Cook, Illinois, have invented a new, original, and ornamental Design for a Stop Light for automobiles, of which the following is a specification, reference being had to the accompanying drawings, forming part thereof.

Fig. 1 is a front elevation of the stop light of my design.

Fig. 2 is a top plan view thereof, and
Fig. 3 is a side elevation thereof.

I claim:

The ornamental design for a stop light for automobiles as shown.

ALBERT KOTLAN.
